HEATING SYSTEMS

Louis H. Crook, Washington, D. C.

Application April 12, 1946, Serial No. 661,786

20 Claims. (Cl. 219—47)

1

This invention relates to an antenna or high frequency heating system, and more particularly to antennae or associated electrodes highly desirable for the use of energy at ultra high and micro-wave frequencies in radio communication or for high frequency for electronic heating purposes, although the invention may have other uses and purposes as will be apparent to one skilled in the art.

This application is a continuation-in-part of 10 and supplants my copending application entitled "Antenna System," filed June 29, 1942, Serial No. 448,947, now forfeited.

At the outset, it should be understood that where the term "antenna" is used herein and in the appended claims, that term is to be construed as having a broad meaning including an electrode of the character which might be used in a high frequency heating system, and the term is not to be construed as limited to its narrow meaning of an electrode or the equivalent used only in radio communication.

One of the important objects of this invention is the provision of an antenna system available for use in diathermy or high frequency heating.

With antenna systems as used for radio communication in the past, especially as a transmitting system, it was well known that differences in soil, differences in ground contour, proximity of conductive elements and other and similar factors adversely affected the systems and caused erratic field distribution. These formerly known systems also were not capable of directing short waves to as high a degree of accuracy and efficiency as is desirable.

Accordingly, it is also an important object of the instant invention to provide an antenna system suitable for the efficient use of energy at very high frequencies in radio communication, which system is not more than negligibly affected by the proximity of conductive objects or by variations of earth contour.

Another object of the invention is the provision of an antenna system or a high frequency heating system in which the source of energy for exciting a short wave antenna or electrode is housed within a shield which extends from the source to partially envelop the antenna or electrode to cooperate with the antenna or electrode as a wave guide.

Also an object of the invention is the provision of a dipole or two pole antenna system in which one pole of a shielded source of energy for exciting the antenna is connected to the antenna, and in which the other pole of the source is connected

2

to a shield for the source and brought to a zone immediately adjacent the antenna.

Electronic or high frequency heating is now recognized as a most useful and advantageous function in many industries. It provides localized heat for cooking, surface hardening, annealing, brazing, bonding, drying, preheating, and softening operations as well as performing countless other and specialized functions. Its chief advantage resides in the tremendous rapidity with which an operation may be performed in comparison with prior methods, and in many cases the operations are not only performed faster, but better and more economically.

However, with high frequency heating arrangements of the character heretofore known, the apparatus consisted mainly of electrodes in the form of two plates spaced one above the other, with the material to be heated forming the dielectric of such a flat plate condenser. With such apparatus, the electric field embraced all surrounding objects, which resulted in energy absorption and consequent waste of power, besides giving rise to great danger to operators and other persons coming in contact with or adjacent to such an electric condenser system. With these prior systems large and costly safety equipment was an essential, and even that safety equipment did not fully protect the operator. Doors to the rooms housing the equipment had automatic switches which shut off the high voltage power, whenever a door was opened. Such additional apparatus was objectionably expensive, to say nothing of its upkeep and the rooms required for its installation. Further, with these formerly known high frequency heating arrangements, equipment acting upon the articles to be heated such as conveyors, presses, etc., interfered with the energy field and absorbed some of that energy. In addition, there was considerable danger at frequent intervals of flash-over occurring.

With the foregoing in mind, it is another important object of the instant invention to provide a high frequency heating arrangement that is substantially completely safe to operators and other persons in the vicinity of the apparatus.

Another object of the invention is the provision of a high frequency heating arrangement producing intense electric fields by way of an enclosed or substantially ungrounded electric circuit which does not materially disturb nor is it materially disturbed by external fields created by other apparatus, or any conductive material or persons coming in contact with the external shielding or electrode of the apparatus, and thus the ar-

55

arrangement eliminates the need for the costly safety equipment essential on devices heretofore known.

Another object of the instant invention is the provision of a high frequency heating system in which the electrodes are arranged one within the other, the outer electrode being the casing of the heating unit or oven itself, and the entire energy field being confined to the space between the electrodes or the space inside the outer electrode, thus producing an electric field of greater intensity which is confined wholly within the outer electrode, resulting not only in more economical operation, but in safety of a high order to the operators and other persons coming within close range of the apparatus.

Also a feature of the instant invention is the provision of a high frequency heating or antenna system in which the operative structure is so arranged as to allow full control of the energy field at all times.

A further object of the invention is the provision of a high frequency heating system in which the work objects or articles to be heated do not adversely affect the energy field.

Another feature of the invention resides in the provision of a high frequency heating assembly so arranged that equipment acting upon the work articles, such as conveyors, presses, and the like, even of massive size, do not for all practical purposes, adversely influence the energy field.

The present invention also provides high frequency heating apparatus of the character that may be predesigned by engineers in various shapes and sizes for special work to be done and provides the particular required types and strengths of field for the particular job.

It is also a feature of this invention to provide a high frequency heating system in which one of the electrodes serves as the oven or casing and the work articles are enclosed thereby.

Still another object of the instant invention is the provision of a high frequency heating or antenna system in which the electrodes and power supply are all part of an enclosed electric circuit.

It is well known that the use of electronic or high frequency heating devices in industry is steadily increasing, and the power requirements and size of the devices are also steadily increasing. Such heating devices of the character heretofore known adversely affect radio broadcasting by setting up disturbances. Consequently, as high frequency radio becomes more and more developed, there will undoubtedly be a considerable problem between the various radio broadcasting stations and the various users of a high frequency heating device, if such heating devices of the character heretofore known are continued in use.

With this thought in mind, it is a very important object of the instant invention to provide a high frequency heating arrangement, not limited in respect to size or power requirements, which will not adversely affect or interfere with radio broadcasting.

Briefly, the instant invention may be physically embodied in an antenna or an electronic heating apparatus consisting essentially of a continuous metal casing terminating in a hood-like or housing portion, which is the first electrode, with a second electrode or antenna member disposed therewithin, the energy source or energy transforming means also being disposed within the conductive casing, one terminal of the energy

source of transforming means being connected to the second electrode or antenna member by conductive means insulated from the casing itself, and the other terminal of the energy source or transforming means being connected to the inside surface of the casing, which inside casing surface functions as the return conductor.

While some of the more salient features, characteristics and advantages of the instant invention have been above pointed out, others will become apparent from the following disclosures, taken in conjunction with the accompanying drawings, in which:

Figure 1 is a diagrammatic showing in the form of a vertical sectional view of an antenna system embodying principles of the instant invention;

Figure 2 is a diagrammatic showing in perspective, with parts in section, of a somewhat different shape of antenna and shield arrangement embodying principles of this invention;

Figure 3 is a fragmentary part sectional, part elevational view of the upper portion of the structure of Figure 2, taken transversely of the apparatus;

Figure 4 is a fragmentary, part sectional, part end elevational view of the present invention arranged in the form of a high frequency heating device, this view also being of a diagrammatic character;

Figure 5 is a fragmentary side elevational view, with parts in section, of the lower portion of the structure of Figure 4;

Figure 6 is a fragmentary part sectional, part end elevational view of a high frequency heating arrangement embodying principles of the instant invention, illustrating diagrammatically the use of a gasoline engine and generator set as a source of the power supply;

Figure 7 is a fragmentary side elevational view, with parts in section, of the lower portion of the structure of Figure 6;

Figure 8 is a diagrammatic side elevational view, with parts in section, of the instant invention arranged in the form of a cooking or baking oven, including conveying means for carrying the articles to be cooked through the oven;

Figure 9 is a fragmentary end elevational view of the structure of Figure 8;

Figure 10 is a fragmentary part vertical sectional, part elevational view, enlarged, of the oven of Figure 8;

Figure 11 is a fragmentary enlarged end elevational view of the structure of Figure 10;

Figure 12 is a diagrammatic fragmentary part sectional, part elevational view showing a still different arrangement of the instant invention in the form of an oven or closed unit for heating and cooking various materials;

Figure 13 is a fragmentary vertical sectional view taken substantially as indicated by the line XIII—XIII of Figure 12, looking in the direction of the arrows;

Figure 14 is a fragmentary end elevational view of the structure of Figure 12;

Figure 15 is a view similar in character to Figure 12 but illustrating a slightly different disposition of the electrodes;

Figure 16 is a fragmentary vertical sectional view taken substantially as indicated by the line XVI—XVI of Figure 15; and

Figure 17 is a fragmentary end elevational view of the structure of Figure 15.

As shown on the drawings:
It will be appreciated that in all figures of

the drawings, the various embodiments of the invention are shown rather in diagrammatic form, in view of the fact that the invention is not centered primarily in specific details of construction, but more to the broad idea of the two electrodes associated with a completely enclosed electric circuit or a substantially enclosed circuit. These electrodes may be of many and various shapes or configurations depending upon whether or not they are designed for the performance of an individual function, and they may in certain instances function as a part of a radiant energy antenna system, and in other instances, may function as a part of a high frequency heating system, maintaining their generally related character throughout.

With reference to Figures 1, 2 and 3, there is shown a two-pole or di-pole arrangement which is suitable for use in an antenna system for radiant energy transmitting purposes. In this arrangement, a source of high frequency energy is generally indicated by numeral 1, and this source of energy is contained within a metallic casing 2 of good conductivity. One pole or terminal of the energy source 1 is connected by way of a conductor 3 to the inside of the casing 2. Associated with this casing is a conductive conduit 4, which, insofar as the electrical circuit is concerned, is an integral part of the casing. The conduit 4 terminates in a housing or hood portion 5 also of good conductivity, and which housing or hood functions as an electrode or pole in the system.

The other pole or terminal of the energy source 1 is connected through a conductor 6 to an antenna member or second electrode 7. The conductor 6 extends through the conduit 4, but is insulated therefrom in any suitable manner or by any suitable means. With this arrangement, the casing 2 together with the conduit 4 and hood portion 5 functions as a shield as well as a conductive part of the electrical system.

In the illustrated instance, the hood 5 is a somewhat hemispherical or bowl-shaped concavo-convex electrode disposed substantially concentrically about the antenna member or electrode 7 which is also concavo-convex and substantially in the form of a hemispherical bowl. The forward portion of the hood or housing 5 is preferably reversely curved inwardly as indicated at 8 so that its terminal edge is in proximity to but in spaced relationship to the edge 9 of the antenna member 7, so that the hood or housing 5 in effect forms a shield around the antenna member. This arrangement provides a gap or space 10 between the confronting edges of the hood 5 and antenna 7, and the width of this gap is, of course, chosen with relation to the potential difference existing between the two electrodes to avoid undue loss of energy.

Likewise, the spacing between the conductor 6 and the conduit 4, the length and diameter of the conduit, and the spacing, shapes, and dimensions of the antenna member 7 and the surrounding hood or shield 5 are suitably chosen with reference to the frequency employed.

The source of energy or transmitter diagrammatically indicated at 1 may be any form of transmitter, oscillator, or other source of energy such as usually comprises batteries, or other sources of current, and suitable electron tubes and associated element for the generation of high frequencies. It is to be understood, however, that the entire transmitter is to be encased within the metallic casing 2. As will more fully appear

later herein, if that source of energy is a transformer, in turn energized by some outside source, at least the secondary of that transformer must be encased within a conductive casing or housing such as the casing 2.

From the foregoing description, it will be noted that the main circuit or energy field of the structure of Figure 1 is a substantially closed electric circuit. The inside surface of the shielding means including the casing 2, conduit 4, and hood 5, functions as the return conductor. Consequently, no material effect on the operation of the antenna system would result in the event an external portion of the shielding means were accidentally connected directly to ground. Likewise, the operation of the antenna system is not adversely affected by adjacent objects, either conducting electrical energy or not, and such objects, such as transmission lines, lead covered cables in the soil, neighboring objects on the ground, in the ground, or above the ground, do not result in losses or erratic field distribution. In short, the soil or ground does not function as the other pole of this antenna system, whereas with the usual transmitting antenna the ground does so function. Nothing outside the shielding means affects more than negligibly the operation of the antenna system, and this feature is of considerable importance especially where it is desired to project sharply directed waves.

As stated above, the instant invention is not limited to any particular size or shape of electrodes, it only being desirable that the outer electrode effectively enclose the inner electrode. In Figures 2 and 3, I have illustrated another arrangement, highly desirable for radio communication purposes, to illustrate that the antenna member and its contiguous shield or outer electrode may be of any form suitable for the projection of radio waves along defined paths. In this instance, there is shown a source of energy generally indicated by numeral 11 completely housed within a conductive casing 12, with one terminal or pole of the energy source connected to the inside of the casing by a conductor 13. A conductive conduit 14 extends from the housing 12 to a trough-like concavo-convex elongated outer electrode or hood 15 provided with closed ends and having an opening 16 through which waves may be projected from a trough-like concavo-convex antenna member or electrode 17 disposed inside the hood 15 in substantially concentric relationship, but spaced from the hood. Obviously, the antenna member or electrode 17 may be supported in any suitable manner, but is kept electrically insulated from the hood 15. This antenna member 17 may be connected by a conductor 18 to the other pole or terminal of the energy source 11. While the conductor 18 extends through the conduit 14, it is, of course, insulated by any suitable means from the conduit.

In connection with the showings in both Figure 1, and in Figures 2 and 3, it will be understood that receiving means may be substituted for the respective transmitters, and the antenna system thus used for receiving signals rather than sending them. In addition, the conduits 4 and 14 may be of flexible tubing, if so desired, so that they may be bent by an operator to position the terminal electrodes 5 and 7 or 15 and 17 relatively to an afflicted portion of the body of a person to direct the emitted waves to that portion in the application of diathermy, or a similar treatment. The zone of application of the emit-

ted energy may be controlled to a fine degree, since the device or system itself comprises a substantially closed circuit and is therefore practically independent of ground.

It will also be understood that either of the arrangements just above described may be utilized for high frequency heating of inanimate objects or materials by locating such objects or materials in proper proximity to the inner electrode 1 or 17, as will more fully be apparent from disclosures hereinafter in connection with the other figures of the drawings.

In Figures 4 and 5, I have illustrated an arrangement or system highly desirable for high frequency heating of various objects. The system, however, incorporates the use of a pair of electrodes very similar in character and disposition to the electrodes above described in connection with Figures 1, 2 and 3, and the same general principles of operation govern.

In the instances of Figures 4 and 5, however, I have illustrated the use of a source of energy in the form of a transformer 19. The primary 20 of this transformer may be connected in any well known manner to any suitable source of current supply in a customary grounded circuit arrangement. The secondary 21 of the transformer is completely covered or enclosed within a conductive metal casing 22 corresponding in general to the conductive casings 2 and 12 above described. One end of the secondary transformer coil is connected to the inside of the casing 22 by a conductor 23.

The particular type of transformer illustrated in Figure 4 is more fully set forth, described, and claimed especially as to its association with a completely enclosed or non-grounded circuit in my copending application entitled "Electric Distribution System," filed June 6, 1942, Serial No. 446,149 now Patent Number 2,533,920.

A conductive conduit 24 extends from the casing 22 to the casing 25 of a control element, and the other end of the secondary transformer coil is connected to the mechanism inside that control element by a conductor 26 extending through the conduit 24 but insulated therefrom. The control element transforms the electrical energy to any desired wattage and frequency that may be required for the particular high frequency heating purpose. Another conductive conduit 27 extends from the casing 25 of the control element to a box-like outer electrode 28 which functions not only as an electrode, but defines and is the oven. It will be understood that there is complete circuit continuity among the casing 22, the conduit 24, the casing 25, the conduit 27, and the outer electrode or oven 28.

A conductor 30 extends from the apparatus inside the casing 25 through the conduit 27 from which it is insulated to an inner or second dome-shaped electrode 31 disposed inside the outer electrode 28. As indicated at 29, the outer electrode has closed end walls covering the end space between itself and the inner electrode 31, but those end walls are so shaped as to define a substantially arcuate opening 32 at each end of the oven through which material to be heated may be placed in position and removed.

From the showing in Figure 5, it will be noted that the inner electrode 31 is not of the same length as the outer electrode, but the ends of the inner electrode terminate well short of the ends of the outer electrode so that this inner electrode is completely enclosed within the outer electrode. Inside the closed ends 29—29 thereof, the

outer electrode is turned upwardly at its lower edge, and between that edge and the corresponding edge of the inner electrode a strip of insulation 33 is disposed on each side of the structure. These insulating strips stabilize the entire construction and effectively insulate the inner electrode from the outer electrode. It will at once be apparent that the inner electrode 31 corresponds to the electrode 1 of Figure 1, and the outer electrode 28 corresponds to the electrode 5 of Figure 1.

In Figures 4 and 5, which as stated above are somewhat diagrammatic showings, I have illustrated how two different items may be cooked or heat treated, although it will be understood that preferably only one such item is subjected to the field of the electrodes at a time.

In the first instance, I have shown a specimen 34 which may be considered a typical example 20 of a section of a large wooden airplane body, or wing surface, that has been glued together and is ready for cooking to facilitate the hardening and 25 drying of the glue used. In this particular case, it is preferable to move the oven over the specimen being treated. To that end, it will be understood that the conduit 27 is flexible to enable the operator to move the cooking oven over the relatively large specimen under treatment. As indicated by the dotted lines 36 in Figure 4, there 30 will be a uniform and intense electric cooking field affecting the specimen 34 as the oven is moved thereover.

A hemispherical arrangement such as shown in Figure 1, or the elongated form shown in Figure 2 which has closed ends, is also practical for such ovens as are adapted to be moved over the article to be heat treated or cooked, or in the case of diathermy, the patient to be treated. In all such forms, the operator is protected from the 40 danger of high frequency, high voltage, etc., within the oven. Also, the material to be treated is fully protected from over-burning or over-treating. In the case of diathermy instruments, both the patient and the operator are protected from 45 the dangerous short circuits or "flash-overs" that exist in present day instruments. In fact, the treated articles are in the electric field of the apparatus and contact only the outer electrode.

To illustrate the use of the oven with the same 50 held stationary and with the object or specimen moved through the oven from end to end thereof, I have selected a specimen 35 which may be plywood in which the laminations are to be effectively glued together by virtue of the developed heat. The electrodes 28 and 31 are preferably shaped in order to produce a uniform and intense electric cooking field across the material 55 as it is passed in a lengthwise or axial direction through the field between these electrodes.

As indicated by the dotted lines 36, a directional 60 field intensity is provided which field is formed by the electric displacement currents of high frequency, in much the same manner as found in the commonly known dielectric of an electric condenser. The shaped electrodes 28 and 31 increase 65 the overall efficiency in the space between them in comparison with the heretofore known flat plate electrodes used in high frequency heating arrangements.

By virtue of the fact that the entire electrical 70 circuit including the two electrodes is a closed circuit, that circuit is not more than negligibly affected by outside influences whether conductive or not. Likewise, the particular high frequency heating circuit does not materially affect

external adjacent circuits, nor will it create any material or noticeable interference with radio reception and broadcasting in the vicinity. The electronic field through the object being heated is fully controlled at all times by the operator and no expensive tuning equipment to prevent radio interference is necessary. No expensive and cumbersome safety equipment is necessary at all, and it is not necessary even to have switches to open the high voltage, high frequency circuit automatically when the door of the laboratory room containing the heating device is opened.

In Figures 6 and 7, I have illustrated another oven arrangement and in this instance I have shown how any form of the present invention may be utilized with a gasoline engine-generator set as a source of energy. In this instance, a gasoline engine is diagrammatically indicated at 37, which engine is coupled to drive an electric generator encased within a conductive housing 38 and a conductive conduit 39 connects the casing 38 with a casing 49 completely enclosing a transformer 41. The primary 42 of this transformer is connected to the inside of the adjacent casing by a conductor 43 at one end, and the other end of the primary is connected by a conductor 44, insulated from the conduit 39, to the generator in the casing 38. The generator is also connected to the inside of the casing 38. The secondary 45 of the transformer is connected at one end by a conductor 46 to the inside of the casing 40. The other side of the secondary is connected through a conductor 47 to the apparatus contained within a conductive control box housing 48 and a conductive tube 49 joins the housing 48 with the casing 40. The conductor 47 is, of course, insulated from the tube or conduit 49. As in the previously described embodiments, conductive tube 50 joins the casing of the control apparatus and an external electrode 51 which defines the heating oven. A conductor 52 passes through the conduit 50, is insulated therefrom, and is directly connected to a second and inside electrode 53, which corresponds to the inside electrode 7 described above in connection with Figure 1.

In this instance, I have illustrated how a relatively large hydraulic press or equivalent apparatus may be used in association with the material 54 to be subjected to heat. The press is diagrammatically illustrated and includes a head 55 actuated up and down by suitable mechanism connected to pull screws or posts 56. The head 55 of the press may for economic reasons be made of plastic material or other non-conductive material, or the pull screws 56 alone may be made of such material. In the event it is desired to make the press head of metal, the inner electrode 53 is preferably well insulated from the press head 55 by the use of a strong dielectric element 57 of substantial thickness. A telescopic arrangement is shown at 58 to permit adjustment of the length of the conductor 52 leading to the electrode 53 to compensate for various thicknesses of material being heated.

In the system shown in Figures 6 and 7, it will be noted that both coils or windings of the transformer 41 are within separate enclosures. It will also be noted that in the type of oven or outer electrode 51 the complete oven is fully enclosed in an equi-potential surface, and this equi-potential surface envelops the entire system, including the source of power as well as

the oven and the necessary internal mechanism and connections. The external metal and mechanical portion of the hydraulic press becomes a part of the external surface and has no electrical space short circuits. It should be noted, however, that in any case in which a metal part passes back and forth in the electric oven, the connection with the oven, such as by one of the posts 56, must be a good electrical one and not insulated in any manner from the outer electrode 51. The external surface of all metal controls, and other apparatus passing through the metal casing 51 must be an electrical part of the outside surface of the external metal casing to insure the external equi-potential surface. Any external metal parts of the entire system may be contacted at any time by the operator without the slightest danger, even though a flash-over may occur within the internal electric system. This is a distinct advantage over any high frequency heating apparatus known or used heretofore.

In Figures 8, 9, 10 and 11, I have illustrated the same general arrangement of electrodes in a high frequency heating system for purposes of cooking or baking objects carried through the oven portion of the system or a conveyor. It should be noted, however, that the conveyor does not pass through the energy field, except for non-insulated pusher elements necessary to move the work articles.

In this instance, an outer box-like electrode 59, provided with an opening 60 at each end thereof, forms the oven. A conductive tube 61 is electrically integral with the electrode 59, and a conductor 62 extends through the conduit 61 and is insulated therefrom. This conductor 62 is connected with an inner plate-like electrode 63 which is completely housed and contained within the outer electrode 59. It should be understood that the inner electrode 63 may be held in proper position inside the outer electrode by a dielectric material of very high specific inductive capacity preferably, such supporting element not being shown in the drawings. It will also be understood that the conduit 61 and conductor 62 are connected in the manner above described to a control mechanism and in such a manner as to form a substantially closed system.

The floor 64 of the outer electrode 59, which floor is a conductive part of that electrode, tapers upwardly at each end as indicated at 65 so that objects may be smoothly carried through the oven between the two electrodes. For moving objects, a conveyor 66 may be provided which is of the endless type traveling over suitable sprocket wheels or the equivalent 67-67. This conveyor is provided with pusher elements 68 at periodic intervals therealong. As best seen in Figure 11, these pusher elements are of substantially fan-shape, and include a narrow neck portion which travels through a slot 69 extending longitudinally of the floor of the outer electrode. Above the neck portion, each pusher element flares out into a relatively wide body for engaging articles to be baked or cooked within the oven. In the illustrated instance, loaves of bread 70 have been selected as examples of a work material to be acted upon by the energy field. The uncooked loaves of bread may be placed upon the left end of the conveyor as viewed in Figure 8, and as the conveyor moves along these loaves of bread are advanced by the pusher elements 68, travel upwardly over the inclined portion 65 of the oven floor, pass through the energy field developed by the

electrodes, and descend the opposite inclined end of the floor and leaving the oven in the form of baked loaves. The floor construction permits the conveyor, with the sole exception of the non-insulated pusher elements, to travel outside the energy field.

With this arrangement, it will be apparent that the electric displacement currents between the electrodes cook or bake the bread throughout uniformly and in an extremely short period of time. The energy field, as in the previously described embodiments of the invention, is an intense field, and concentrated so that the article being heated gets the full value of the energy field. There is no danger to the operator, and no necessity for expensive safety apparatus, or need for tuning to prevent radio interference.

In Figures 12, 13 and 14, I have illustrated another oven arrangement, which is highly desirable for heating fluid materials that are forced through the oven under various pressures, for purposes of pressure molding, extrusion processes, and the usual preheating or cooking of plastics just prior to form molding. In this instance, an oven 71 of tubular shape is provided, and as in the previous examples, this oven is also a part of an enclosed electrical circuit. At each end thereof, the oven 71 is provided with a hollow neck portion 72 for the entrance and exit of material to be heated. It makes no difference which direction the material travels through the oven. In this instance, however, I have shown an arrangement for the use of spaced or separated inside electrodes 73 and 74 completely housed within the oven 71. A conductor 75 which passes through a conductive conduit 76 leads to the electrode 73, and a similar conductor 77 passing through a conductive conduit 78 leads to the electrode 74. The conduits 76 and 78 are electrically integral with the oven 71. It will, of course, be understood that the conductors 75 and 77 lead to the same connection in a control device, and the conduits 76 and 78 are each connected to the casing of the control device, in the same manner as the single conductors and single conduits above described.

With reference more particularly to Figure 13, it will be seen that the inside electrodes 73 and 74 are shaped to form a part of the circumference of a circle. Between the electrodes 73 and 74, at equally spaced distances, are sub-outer electrodes 79 and 80 also shaped in conformity with portions of the circumference of a circle, the same diameter as the circle partially defined by the electrodes 73 and 74. The electrodes 79 and 80 as indicated at 81—81 are conductively connected with the oven 71. As indicated at 82 in Figure 13, the space 83 between the conduits 76 and 78 and the respective conductors, and between the oven 71 and the inside electrodes and sub-electrodes, is preferably filled with an insulation material of high dielectric capacity, which material serves to fix the electrodes in position and to insure the correct paths of electric displacement currents through the material to be heated or cooked. The displacement currents in the electric circuit from electrode 73 to sub-electrode 79 are preferably so arranged as to be in exact phase with those operating in the circuit from electrode 74 to sub-electrode 80 to cause a more intense and more uniform electric displacement field in the same direction at the same time.

In Figures 15, 16 and 17, I have illustrated a modification of the structure of Figures 12, 13 and 14, wherein only one substantially semi-cylindrical inside electrode and one substantially semi-

cylindrical inside sub-electrode are utilized. In this instance, a conductive oven 84 having hollow neck openings 85—85 at opposite ends thereof is provided, and a conductive conduit 86 is electrically integral with the oven. Inside the oven there is disposed an inner electrode 87 connected by a conductor 88 to a suitable control station to the casing of which the conduit 86 is also connected as above described. The inner electrode 87 is substantially semi-cylindrical in shape, but is not a full half circle so that space is allowed between it and a similarly shaped and oppositely disposed sub-electrode 89 connected to the oven 84 as indicated at 90. It will be understood that the space 91 between the inner electrode and the oven and between the conductor 88 and the conduit 86 is preferably filled with insulation such as a ceramic lining or other dielectric medium to fix the electrodes in position axially within the oven. This insulation is preferably shaped to insure the best streamlined flow of the material through the oven and insure the best contact of that material with the electrodes.

In connection with the showing in Figures 12 to 17, inclusive, it will be noted that the material passing through the respective ovens actually contacts the two electrode arrangements so as to in effect short circuit the electrodes. Thus, the energy field is extremely concentrated insofar as the material to be heated is concerned.

From the foregoing, it is apparent that I have provided a novel electrical system which may function as an antenna system or as a high frequency heating system, or as a diathermic treating device. Two overall types of oven have been described, first, a completely enclosed oven or radiant energy transmission system totally surrounded by a metal conductor, and second, a radiant energy transmission system in which a portion of the energy field lies outside the metal casing or external antenna in predetermined spaced relations. In the first case all radio interference or danger to the operator is completely eliminated. In the second case we have protection, in as substantial manner as desired, for the commercial radio field, as well as ample protection to the operators of the apparatus and the material or patent to be treated. It will further be noted that the invention is economical to build and operate, and highly durable.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A dipole antenna system comprising an antenna having a peripheral edge and forming one pole of the system, a metallic shielding casing having a terminal portion disposed about said antenna and extending forwardly of said edge and forming the other pole of the system, a source of energy within said casing, a conductor within said casing and connecting one terminal of said source to said antenna, the other terminal of said source being connected to said casing.

2. A dipole antenna system comprising an antenna formed of a curved metallic member and forming one pole of the system, a source of energy, a metallic casing housing said source, a conductor within said casing and connecting one terminal of said source to said antenna, the other terminal of said source being connected to said casing, said casing having a curved terminal por-

tion thereof forming the other pole of the system and disposed about said antenna in shielding relation thereto.

3. A dipole antenna system comprising a metallic casing, a source of energy housed within said casing and having one terminal connected to said casing, said casing having a tubular extension terminating in a curved shielding member forming one pole of the system and shaped to present a front opening, a curved metallic antenna member forming the other pole of the system and placed within said curved shielding member and rearwardly of said opening, and a lead within said casing connecting said antenna with the other terminal of said source.

4. A dipole antenna system comprising a conductive metallic casing closed at one end and having its other end curved and forming one pole of the system and provided with an opening, a curved antenna member forming the other pole of the system and entered in said casing and adjacent said opening, a source of energy in said casing, a conductive lead in said casing connecting one terminal of said source to said member, the other terminal of said source being connected to said casing to conductively bring said other terminal into proximity to said antenna member.

5. A dipole wave emitter comprising a metallic casing having a portion shaped to define a hollow first electrode, a second electrode entered in said first electrode, energy transforming means within said casing, a conductor within and insulated from said casing and connecting one pole of said transforming means with said second electrode, the other pole of said transforming means being connected to said first electrode.

6. A transmitter comprising an elongated metallic casing closed at one end and terminating at the other end in a bowl-shaped portion, a source of power contained within said casing and disposed adjacent the closed end thereof, a bowl-shaped member disposed within the bowl-shaped terminal portion of said casing and in spaced and insulated relation thereto, conductor means in said casing connecting said bowl-shaped member and one terminal of said source and in insulated relation to said casing, the other terminal of said source being conductively connected to said casing.

7. A transmitter comprising an elongated metallic casing closed at one end and terminating at the other end in an elongated curved trough-shaped portion, a source of power in said casing and disposed therein remote from said terminal portion, an elongated curved trough-shaped member disposed within said terminal portion and in spaced and insulated relation thereto, a conductor within said casing connecting said trough-shaped member to one terminal of said source and being in insulated relation to and shielded by said casing, the other terminal of said source being conductively connected to said casing.

8. A transmitter comprising an elongated metallic casing closed at one end and terminating at the other end in a bowl-shaped portion having a free peripheral edge, a source of power in said casing and disposed therein remote from said terminal portion, a bowl-shaped member disposed within said terminal portion and in spaced and insulated relation thereto, said bowl-shaped member having a free peripheral edge disposed in the terminal portion inwardly of the free peripheral edge of said terminal portion, a conductor connecting said bowl-shaped member with

one terminal of said source, said conductor being disposed within said casing in insulated relation to and shielded by said casing, the other terminal of said source being conductively connected to said casing.

9. A dipole antenna assembly comprising a curved metallic hood having a front opening and forming the terminal of an elongated casing and one pole of the antenna, an elongated metallic casing closed at one end and having said hood as its terminal at the other end, a source of power within said casing and remote from said hood, a curved metallic member in said hood and in spaced and insulated relation thereto and forming the other pole of the dipole antenna, a conductor within said casing connecting said curved member to one terminal of said source, said conductor being disposed in insulated relation to and shielded by said casing, the other terminal of said source being connected to said casing.

10. A dipole antenna assembly comprising an elongated metallic casing closed at one end and terminating at its other end in a hood having a front opening, said hood being one pole of the dipole antenna, a source of energy in said casing and remote from said hood and having one terminal conductively connected to said casing, a curved metallic member entered in said hood and in spaced and insulated relation thereto, said member being the other pole of said dipole antenna, a conductor within said casing connecting said member with the other terminal of said source, said conductor being disposed in insulated relation to and shielded by said casing.

11. A dipole antenna assembly comprising an elongated metallic casing closed at one end and terminating at its other end in a curved hood having a front opening, said hood being one pole of the dipole assembly, a source of energy in said casing and remote from said hood, conductor means in said casing and in spaced and insulated relation thereto, one end of said conductor means being connected to one terminal of said source and the other end of said conductor means terminating in said hood to provide the other pole of the dipole assembly, the other terminal of said source being conductively connected to said casing.

12. A dipole antenna assembly comprising an elongated metallic casing closed at one end and terminating at its other end in a curved hood having a front opening, said hood being one pole of the dipole assembly, a source of energy within said casing, a conductor in said casing and in spaced and insulated relation thereto and shielded thereby, said conductor having one end connected to one terminal of said source and having its other end entered within said hood to provide the other pole of said dipole assembly, the other terminal of said source being conductively connected to said casing.

13. In an antenna assembly, an ungrounded arrangement including an antenna member, a conductive casing terminating in a hood about but spaced from said antenna member, a source of energy in said casing, means connecting one terminal of said source to the casing, and a conductor insulated from said casing but disposed therewithin and connecting the other terminal of said source to said antenna member.

14. A self-contained ungrounded antenna assembly, including a hollow conductive casing terminating at one end in a hood-like portion, an antenna member disposed in said hood-like portion with its terminal edge spaced from but in

proximity to the edge of said hood-like portion, a source of energy in said casing, means connecting a terminal of said source to said casing, and a conductor running through said casing but insulated therefrom and connecting the other terminal of said source to said antenna member, whereby the energy field is internal and the inside surface of said casing serves as a return conductor.

15. In a closed radiant energy transmission system, a pair of electrodes one within the other but spaced apart, hollow conductive means electrically integral with one of said electrodes, a source of energy in said hollow conductive means, a conductor connecting one terminal of the source to the inside of said hollow conductive means, and a conductive means extending through said hollow conductive means but insulated therefrom connecting the other terminal of the source to the other of said electrodes.

16. In a closed radiant energy transmission system, an outer electrode in the form of a housing, an inner electrode completely contained within the outer electrode but spaced and insulated therefrom, hollow conductive means electrically integral with the outer electrode, a source of energy in said means, one terminal of said source being connected to the inside of said means, and means extending within said hollow conductive means but insulated therefrom connecting the other terminal of said source with the inner electrode.

17. In an enclosed radiant energy heating system, an outer electrode in the form of a housing, an inner electrode completely contained within the outer electrode but spaced and insulated therefrom, hollow conductive means electrically integral with the outer electrode, a source of energy in said means, one terminal of said source being connected to the inside of said means, and means extending within said hollow conductive means but insulated therefrom connecting the other terminal of said source with the inner electrode, said electrodes being arranged to define a path for work material which material directly contacts both electrodes.

18. In a wave transmitter of the character described, an ungrounded arrangement including an electrode, a conductive casing terminating in a hood forming a second electrode about but spaced and insulated from the first electrode, a source of energy in the casing, means connecting one side of said source to the casing, a conductor in the casing and insulated therefrom connecting the other side of said source to the first electrode, said second electrode having closed ends except for work passage openings, and the

first electrode being disposed above the work path through said openings.

19. In a wave transmitter of the character described, an ungrounded arrangement including an electrode, a conductive casing terminating in a hood forming a second electrode about but spaced and insulated from the first electrode, a source of energy in the casing, means connecting one side of said source to the casing, a conductor in the casing and insulated therefrom connecting the other side of said source to the first electrode, said second electrode having closed ends except for work passage openings, and the first electrode being of transversely arcuate shape and defining a work material path between said openings.

20. In a closed radiant energy transmission system, a pair of electrodes one within the other but spaced apart, hollow conductive means electrically integral with one of said electrodes, a source of energy in said hollow conductive means, a conductor connecting one terminal of the source to the inside of said hollow conductive means, a conductive means extending through said hollow conductive means but insulated therefrom connecting the other terminal of the source to the other of said electrodes, the outer electrode being in the form of a housing with the ends closed except for opposed openings through which work material may enter and leave, the inner electrode being adjacent the path of material, and conveying means to carry material through the outer electrode from end to end thereof.
